ROBERT B. CARSLEY, OF BOSTON, MASSACHUSETTS.

Design No. 3,363, dated February 9, 1869.

DESIGN FOR A CANCELLING AND EMBOSsing-STAMP.

The Schedule referred to in these Letters Patent and making part of the same.

To all persons to whom these presents may come:

Be it known that I, ROBERT B. CARSLEY, of Boston, in the county of Suffolk, and State of Massachusetts, have invented a new and ornamental Design for a Cancelling and Embossing-Stamp; and I do hereby declare the same to be described as follows, reference being had to the accompanying drawings, of which—

Figure 1 is a side view, and

Figure 2, a front elevation of it.

In the said drawings—

A is the base-plate, on which is a die-plate, B, and the hind legs of a lion are elevated in manner as shown.

The remainder of the lion, C, which, at the rump, is hinged to the hind legs, has the fore paws resting on another die-plate, D, which projects from them in manner as exhibited, each of the two die-plates being

of a rectangular shape. The paws of the front legs project over the upper edge of the upper die-plate.

A spring, E, resting on a projection from the base-plate, extends up into a recess in the body of the lion, and serves to raise the body into an inclined position, relatively to the base-plate.

The design in question is composed of the lion, the die, and bed-plates, arranged and formed as described and represented.

I claim the said design for a cancelling-stamp or press.

ROBERT B. CARSLEY.
